VARIABLE TIMER

Ernest Richard Freeberg, Moline, Ill., assignor to
 Eagle Signal Corporation, Moline, Ill., a corporation of Massachusetts

Application July 3, 1935, Serial No. 29,624

22 Claims. (Cl. 200—27)

This invention relates to variable timers, and more particularly to those utilized, in connection with the signaling systems adapted for controlling the movements of highway traffic, for supervising or maintaining a plurality of individual traffic signal control mechanisms, for diverse intersections, in predetermined functional relationships one to another.

Variable timers heretofore available for supervising groups of traffic signal control mechanisms, such as those groups ordinarily utilized at highway intersections for effecting so-called "progressive" control of the displays of signal aspects, have embodied features exceedingly intricate and complicated in character, as exemplified by the clutches, oil baths, solenoids and the like, which have been employed for effecting revisions of the cycle or operating speed of such timers.

Furthermore, such complexities of character have resulted in the adoption of designs and methods of manufacture which have rendered the resultant mechanism subject to undesirably frequent disarrangement and, when disarranged, requiring the services of those highly skilled and having special training for effecting repair and readjustment.

It is, therefore, an important object of this invention to provide a variable timer of simple, sturdy and compact design, such as will be readily susceptible to adjustment, maintenance and/or repair, by persons of ordinary intelligence, without recourse to special facilities.

It is another important object of this invention to provide a variable timer capable of effecting a plurality of types of operating cycles, each differing from another in cycle time or duration, and each accomplished without the utilization of complicated speed changing devices.

Another important object of this invention is to provide a variable timer having a constant speed driving motor, a variable speed timing device and simple, compact change gear mechanism intermediate the motor and the timing device for readily effecting diverse operating characteristics of said timing device.

Another important object is to provide a variable timer wherein speed changes may be readily accomplished without manual adjustments other than necessary for selectively indicating the desired speed.

Another important object of this invention is to provide selector mechanism which may be readily set indicative of a comparatively extensive revision of timer operating speed, and which

will thereafter act to automatically accomplish attainment of the selected operating speed.

Another important object is to provide a variable timer with speed changing facilities including delaying mechanism whereby speed changing adjustments may be accomplished only at specific periods in the operation of the timer.

Another important object is to provide a variable timer with speed changing facilities including change limiting mechanism whereby speed changes may be accomplished only in steps of predetermined magnitude and with predetermined relatively timed intervals between changes.

A further important object of this invention is to provide improved variable timer mechanism which, for the accomplishment of all, any one or of any group of the foregoing objects, shall be of greater effectiveness and reliability, composed of a smaller number of parts severally characterized by strength, durability and facility of assembly, as well as amenable to a lower cost of manufacture.

Other and more specific objects and advantages will appear in the following description of an illustrative embodiment of this invention or will be apparent therefrom to those skilled in this art.

In a preferred embodiment of this invention, the foregoing objects and others ancillary thereto are accomplished as follows:

A more or less constant speed driving means, such as a synchronous motor, is provided for driving a splined or slotted shaft upon which gear changing mechanism is so keyed or secured as to be rotated thereby while slidably along the length of said shaft.

A group of gears of successively diverse sizes is fixed upon a shaft adjacent to said splined shaft in such order as to present the general outline of a truncated cone, and preferably in such relative arrangement that at some point of the circumference thereof, the teeth of all gears will be in alignment.

A gear is slidably supported and driven by said splined shaft, and has operatively associated therewith a pinion with a partially bevel face; which gear and pinion are so supported that they will retain operative relationship throughout movement of said pinion to positions where it may mesh with and thereby drive various ones of said cone of gears.

A cam shaft, having a series of cams fixed thereon for controlling desired circuits, is geared to the shaft upon which said cone of gears is fixed.

Selector mechanism including a notched rotatable dial having an attached barrel further includes two oppositely tensioned springs respectively associated with two arms which, in turn, lie in the path of a pin moving with a gear. Said gear meshes with a gear rack carrying a shifting fork whereby, through said gear pin, said gear, said gear rack and said shifting fork, said springs urge movement of said arms to actuate said gear changing mechanism responsive to presettings of said selector mechanism. As a result of such urge, said beveled pinion is moved into engagement with that cone gear representative of the desired timer operating speed to which said selector mechanism is at any time preset; such movement of the pinion also serving to so place the gear train as to maintain suitable cooperative relationship therewith.

Change delay mechanism is provided which includes a change delay shaft having fixed thereon a group of disc-like members so associated as to form a drum-like structure which will be hereinafter referred to as a "delay drum".

Raised segmental sections or portions carried by these disc-like members are disposed in progressively presented relationship so as to provide a generally spiral effect about said structure.

The delay shaft is geared to said cone gear shaft for rotation at a speed preferably somewhat slower than that of said cone shaft.

A guide tongue associated with said gear changing mechanism is arranged to engage the sides of the raised portions of said disc-like members to the end that movement of said gear changing mechanism along said splined shaft from one associated cone gear to another is permitted to occur only in steps predetermined as to magnitude and as to timed relationship with the rotation of said gear cone; the timing of these steps being preferably such that they will occur only during the portions of the revolution of the gear cone when the aligned teeth thereof are presented to the beveled faced pinion.

For the purpose of facilitating a ready understanding of this invention and what are considered to be its novel characteristics, an embodiment thereof is represented in the annexed drawing and hereinafter described. Such embodiment, though practical, is by no means the only one which the invention may assume, wherefore the invention is not confined to any particular degree of conformity with the more or less diagrammatic representation of the drawing but may be changed and modified in various particulars, so long as such changes and modifications make no material departures from the invention as more particularly set forth in the annexed claims.

In the accompanying drawing, Figure 1 is a diagrammatic, isometric representation of a variable timer embodying this invention, with certain parts exaggerated in scale and/or cut away in section to more clearly disclose the intended relationships and the functions of the mechanism, and

Fig. 2 is a fragmentary detail view of certain parts of Fig. 1, showing a preferred form of a part thereof.

This variable timer is of a type which is sometimes referred to by the term "master timer", and comprises a synchronous motor M for imparting rotation to a shaft 112, at a suitably constant speed, through reduction gearing comprising a worm gear 102, which is fixed upon a shaft

100 of motor M and which meshes with a worm wheel 104; a pinion 108, which with the worm wheel 104 is fixed upon a shaft 106; and a gear 110, which is fixed upon a shaft 112 and which meshes with a pinion 108.

Change gear mechanism G is supported upon the shaft 112 and a guide rod 116 for a sliding movement lengthwise on said shaft and rod; said rod being supported in fixed relation to said shaft, and said shaft having a spline or key way 118 formed therein for said portion of its length as will permit suitable movement of said change gear mechanism along the length thereof, as will be hereinafter more fully explained.

Said change gear mechanism includes a head 114 which engages the rod 116 to be guided thereby, and further includes arms 118, 118', which are journaled upon the shaft 112.

A guiding tongue 132 is carried by the head 114 and is pivoted at 129 for a purpose which will be hereinafter more fully explained. This tongue is so formed and supported that it may be swung around said pivot by and out of the path of an engaging one of the projecting portions 188, 188', etc. A flat spring 131 is so associated with said tongue, and of tension such as to overcome any tendency thereof to swing due to the friction between said tongue and the side of any of said raised portions, while permitting said tongue to be swung out of the path of any raised portion if engaged by the leading end thereof.

The pinion 128 is situated between the arms 118, 118' of the mechanism G, so as to move therewith along the length of the shaft 112; said pinion 128 engaging the spline or key way 118 therein so as to be rotated thereby. A gear 122 is journaled upon a stud 126 between said arms 118, 118' and meshes with the pinion 128. A beveled driving pinion 130 is journaled upon a stud 126, and is also situated between said arms 118, 118' and meshes with the gear 122 to be driven thereby. Said driving pinion 130 has formed therein conventional spur gear teeth 130' and, cut in alignment therewith, spur beveled gear teeth 130''.

A shaft 140 has fixed thereon twelve gears 142, 144, 146, 148, 150, 152, 154, 156, 158, 160, 162 and 164 of progressively diverse size, and so relatively positioned on said shaft as to collectively form, in effect, a truncated "gear cone" with the various components of which the pinion 130 may be brought into meshing relationship by movement of the change gear mechanism G along the splined shaft 112. Said gears are further so relatively fixed upon said shaft that, when the parts are positioned as shown, there will be substantial alignment between the teeth of all of said gears which are then in position to be engaged by the pinion 130; to the end that, when the shaft 140 is so positioned, movement of the pinion 130 from one to another of said gears will be facilitated.

The arms 118, 118' are so associated with the change gear mechanism G that they may rock around the shaft 112 to an extent sufficient to carry the stud 126 to all of the positions which it should assume in order that the pinion 130 may be brought into suitable driving relationship with any one of the cone of gears carried by the shaft 140; said arms being urged, as by gravity, to swing around the shaft 112 in such direction as to carry the pinion 130 toward the gears of said cone.

A gear 166 and a pinion 168 are also fixed upon the shaft 140. Gear 166 acts through an intermediate gear 170, an intermediate pinion 171 and a driven gear 172 to rotate a cam shaft 174. 5 Pinion 168 acts through an intermediate gear 176, an intermediate pinion 178 and a driven gear 180 to rotate a shift delay shaft 182 upon which said gear 180 is fixed.

The train of gears comprising gears 166, 176, 10 178 and 180 may be such as to effect a suitable gearing reduction ratio. As shown, such ratio is six to one between shafts 140 and 182 or, in other words, such gearing effects a reduction which will make it necessary for shaft 140 to 15 complete six revolutions for each revolution completed by shaft 182.

A shift delay drum D is fixed upon the shaft 182. This drum comprises a unitary assembly including circular end discs 184, 186, and a group 20 of guiding discs with eleven associated segmental raised portions of which the five nearest the right end and the four nearest the left end of the group are shown and respectively numbered 188 to 192 and 195 to 198. These raised portions are so situated 25 as to form abutments for the tongue 132, for thereby obstructing movement of the head 114 lengthwise the rod 116 and the shaft 112, and are so situated that the pinion 130 will be positioned in proper meshing relationship with an appropriate one of the cone gears when said tongue is situated between the paths of rotation of any adjacent two of said raised portions. The circumferential length of said raised portions should be such that, due to the rate of rotation of said 30 drum D, a desired length of time will elapse between permitted steps in the movement of the pinion 130, as it is carried from one to another of the cone gears. As shown, each of these raised portions has a circumferential length of approximately one-half of the periphery of the drum D. 35 The circumferential positioning of the raised portions of said drum D is further such, with regard to the gearing ratio between shafts 140 and 182, that whenever, during rotation of shaft 182, the trailing end of any one of said projections is 40 withdrawn from the path of the tongue 132, the cone of gears carried by the shaft 140 will then be in such portion of a revolution that the aligned teeth thereof will be in the path of axial movement of the pinion 130, so as to facilitate transfer 45 thereof from one to another of said gears.

The length of the raised portions of said drum D may be, as indicated in Fig. 1, approximately one-half of the circumference; however, best results will be obtained, for reasons hereinafter 55 more fully explained, if said raised portions extend nearly around said drum, as indicated in Fig. 2, the leading end of each projection being spaced from its trailing end by a distance slightly greater than the width of the tongue 132, so that 60 said tongue may freely pass therebetween.

In any event, the end spaces of the adjacent raised portions should be circumferentially displaced one from another, so as to provide a spiral effect; or the surfaces of the drum D otherwise 65 so formed as to include structure presenting a generally spiral effect and situated in the path of and for governing axial movement of said tongue 132, to thereby establish a progressive timing for movement of said tongue.

70 Circuit controller mechanism is provided, comprising cams 200, 202 and contact arms 204, 206 journaled upon a pivot shaft 208. The contact arm 204 has contacts 212 associated therewith, and a spring 210 which urges movement of 75 said arm toward the cam 200, so that the con-

tacts 212 will be closed only while the raised portion of said cam is withdrawn from the path of said arm. Contacts 216 are so associated with the contact arm 206 that when the free end of said arm is supported by the raised portion of cam 202, said contacts will be closed, and a spring 214 is so applied to said arm that when the raised portion of said cam is withdrawn from the free end thereof, the contacts 216 will be separated. The cams 200, 202 are fixed upon the 10 shaft 174; and, although here shown as being of plain disc type, these cams may be of any well-known construction, either solid and fixed as shown, or adjustable.

Selector mechanism S is provided for effecting 15 desired speed revisions. This mechanism includes a notched disc 230 and a barrel or sleeve 232 which moves with and is supported thereby. Said disc has indicia associated with the notches therein and is journaled upon a shaft 234 for rotation, together with the barrel 232, independently of said shaft. A flat coiled spring 236 is contained within said barrel and has the inner end thereof attached to the shaft 234 and the outer end secured to the inner surface of said barrel 232, so that counter-clockwise displacement of said barrel with relation to said shaft will wind 25 said spring.

A sleeve 244 is freely journaled upon said shaft 234. A second flat coiled spring 248 has the inner 30 end thereof secured to said sleeve and the outer end thereof secured to said barrel 232 so that clockwise displacement of said drum with relation to said sleeve will wind said spring.

A gear 242 is situated adjacent to the barrel 35 232 and is freely journaled upon the shaft 234. A gear rack 256 meshes with said gear 242, and is carried by a guide bar 258 of cross section suited for slidable cooperation with a groove in a suitable support (not shown). A shifting fork 260 moves with said rack and bar and engages the 40 supporting head 114 for moving same along the length of the shaft 112.

A pin 240 fixed in the gear 242 projects from 45 said gear into the barrel 232.

Arms 238 and 246 are fixed upon the shaft 234 and the sleeve 244, respectively, in such relationship that the springs 236 and 248 are at all times somewhat tensioned for urging counter-clockwise movement of the arm 238 and clockwise movement of the arm 246; the free ends of these arms 50 extending into the path of movement of the pin 240.

A limiting block 250 is fixed upon the inner surface of the barrel 232 and extends into the paths of the free ends of the arms 238 and 246; the form of said block being preferably such that, when in radial alignment with the pin 240, it 55 will insure separation of the arms 238 and 246 as great as or somewhat in excess of that which 60 would be caused by said pin 240.

A locking lever 272, pivoted independently of the disc 230 at 274, carries an operating handle 276 and is provided with a locking projection 278 for engaging one or another of the notches 280 formed in the periphery of the disc 230, to thereby 65 retain said disc in positions respectively representative of the various ones of the available operating speeds for the cams 200, 202.

Conductors 286, 288 lead from the motor M to 70 a suitable current supply source. Conductors 288, 290 and 292, 294 lead from the respective pairs of cam controlled contacts 212 and 216 to such external current paths as are to be controlled thereby.

Operation

Assuming that current of suitable characteristics is applied through the conductors 286, 288 for causing the motor M to operate at intended speed, and that the parts are positioned as shown in the drawing, operation of the variable timer hereinbefore described will be as follows:

Motor M will cause shaft 100 and worm gear 102 to be rotated in the direction indicated by the arrow at a suitably constant speed. Gear 102 will act through wheel 104, shaft 106, pinion 108 and gear 110 to rotate splined shaft 112. Pinion 120, gear 122 and beveled driving pinion 130 will thus be caused to rotate pursuant to the rotation of shaft 112 and thereby to effect corresponding rotation of cone gear 146 and of the shaft 140.

Such rotation of the shaft 140 will be transmitted to shaft 182 through the gear train 168, 176-178, 180, and to cam shaft 174 through the train of gears 166, 170, 171 and 172. The cams 200, 202 will thus be caused to rotate at desired speed in counter-clockwise direction due to the speed of rotation of the motor shaft 100, which shaft drives said cams through the gear ratio indicated by the drawing. The operating cycles or revolutions of these cams will be accomplished in 77½ seconds so long as the disc 230 of the selector mechanism S is positioned (as shown) with the one of its notches 280 which is midway between the indicia 75 and 80 positioned for engagement by the projection 278 of lever 272.

From the foregoing it will be evident that the condition of the current paths through conductors 288, 290 and 292, 294 will be subjected, every 77½ seconds, to the cycle of changes represented by the contours of the cams 200, 202. It will also be evident that the timing of such cycles will be accurately accomplished.

For changing such timing, the projection 278 should first be swung away from the disc 230, by grasping the handle 276 carried by the lever 272, and said disc should then be so rotated as to bring in alignment with said projection 278 such one of the notches 280 as is representative of the desired cycle time.

Thus, for example, if it is desired to shorten the cycle time from 77½ to 60 seconds, the notch 280 designated by the indicia 60 should be positioned in alignment with the projection 278, and the lever 272 should then be rotated to its normal position, carrying the projection 278 into such notch 280.

Such movement of disc 230 and barrel 232 to the 60 (second) position, will correspondingly move both ends of the spring 248; the outer end of said spring being directly moved with the barrel 232, and the block 250 acting through the arm 246 and the sleeve 244 to correspondingly rotate the inner end of said spring, so that there will be no resultant alteration in the tensioning thereof.

On the other hand, such movement of the disc 230 will, through the barrel 232, cause the outer end of spring 236 to be rotated in a counter-clockwise direction.

Since arm 238 (and, therefore, the inner end of spring 236) may, at this time, move counter-clockwise only as permitted by corresponding movement of pin 240, said spring will be "wound" to such extent as the angular displacement of the outer end thereof may exceed that (if any) then permitted for the inner end thereof by rotation of the gear 242 responsive to the urge of said spring.

From the foregoing it will be seen that the

gear 242 will urge movement to the left (as shown by the drawing) of the rack 258 and the parts operatively associated therewith, so that the tongue 132 will be moved to the left until it encounters the one of the segmental raised portions then situated in its path.

If, at such time, the parts are so positioned that the raised portion 190 is in the path of the tongue 132, the pinion 130 will continue to engage the gear 146 until said raised portion 190 is withdrawn from the path of said tongue 132, when said pinion 130 will be carried into engagement with the gear 148. This action will occur at a time when the teeth of these gears which are presented to said pinion are in alignment.

Since, as hereinbefore explained, a gearing ratio has been indicated by the drawing, between shafts 182 and 140, such that the former makes but one revolution to six revolutions of the latter, the pinion 130 will thereafter be retained, by the raised portion 191, in driving engagement with the gear 148, until the shaft 140 has completed three revolutions, and has again brought the aligned teeth of the cone gears into the path of the pinion 130; whereupon, the raised portion 191 will be withdrawn from the path of the tongue 132, and the spring 236 acting through the intervening parts as already explained will cause the pinion 130 to be moved from engagement with the gear 148 and into engagement with the gear 150. The leftwise movement of the tongue 132 will then be arrested by the raised portion 192.

With disc 230 thus retained (by the projection 278) in position representative of a 60 second cycle, pinion 130 will be moved to the left, from the position just described, in a succession of steps each of which is of a magnitude equivalent to the relative spacing of the respective gears 152, 154, 156, 158 and 160 of the gear cone. For the reasons hereinbefore explained, such steps will occur singly following respective groups of three revolutions of the shaft 140, and operation, pursuant to the alteration of ratio established by such change, will continue until the pinion 130 reaches and meshes with the cone gear representative of the selected cycle duration which, in the foregoing example, would be gear 160 representative of a 60 second cycle.

The described action of the shaft delay drum D not only serves to facilitate gear ratio transfers but also serves to prevent sudden or abrupt occurrence of extensive changes in speed which may be more or less detrimental to mechanisms affected.

By utilizing the drum D in the application of this invention for supervising systems comprising a plurality of traffic signal control mechanisms, changes in the speed of operation cycles of such mechanisms may be accomplished in easy, gradual steps without noticeably affecting the so-called "progressive" traffic movement permitted by the signals of the system.

When the parts have attained the positions as just described, the pin 248 will cause such positioning of the gear 242 and intermediate parts that the tongue 132 will be retained substantially midway between the paths of the raised portions 196 and 197; and the pinion 130 will be positioned for properly meshing with and effectively driving the gear 160.

Due to the extent in which the diameter of gear 146 exceeds that of gear 160, it is evident that, upon attainment of the setting just de-

scribed, the shaft 148 will be rotated more rapidly, responsive to the same speed of the motor M and parts directly driven thereby; the gearing being so proportioned that, with this revised 5 setting, the cycle time of the cams 200, 202 will be 60 seconds.

When it is desired to increase the cycle length, the disc 230 of the selector mechanism S should, as hereinbefore described, be so moved that the 10 notch representative of the desired cycle duration will be in alignment with the projection 278.

Such cycle lengthening movement will wind the spring 248 and thereby cause the arm 246 to urge the pin 249 to rotate the gear 242 in 15 clockwise direction while not altering the condition of spring 236.

The fork 268 will thus be urged to move from left to right and, as such movement is permitted by the cooperation of the raised portions 188, 20 189, etc. with said tongue 132, the pinion 130 will be moved, in a manner corresponding to that hereinbefore described with relation to its movement in the opposite direction, until said pinion is properly meshed with a gear of such diameter 25 as will enable it to drive the cams 200, 202 at the desired speed.

Movement of the mechanism G—especially that from smaller to larger gears—is facilitated by the bevel cut teeth 130" which serve for 30 maintaining continuous driving engagement during transfer of the pinion 130 between gears of differing diameter.

The discs 184 and 186, at the respective ends 35 of the drum D, serve as extreme limits for the axial movement of the tongue 132.

When the disc 230 is rotated for the purpose 40 of changing the cycle length, the first step of the change may, under certain circumstances, occur immediately. Such circumstances involve the positioning of the drum D so that movement of the tongue 132 urged responsive to such rotation of said disc 230 will not be blocked by that one 45 of the raised portions 188, 189, etc. whose path is nearest to said tongue on the side thereof toward which it is urged.

Thus, if the parts are positioned as indicated in Fig. 1, at a time when the disc 230 is rotated counter-clockwise, it is evident that the raised portion 189 will not obstruct the resultantly urged 50 movement of tongue 132, and said tongue will immediately move into engagement with raised portion 181 and, if the movement of the disc 230 has been such as to call for more than one step 55 of transfer of the pinion 130, a second step of movement will thereafter quickly ensue, when the raised portion 181 is withdrawn from the path of the tongue 132 by the further rotation of the drum D.

If, however, the preferred arrangement indicated by Fig. 2 is employed, the tongue 132 will be permitted to move responsive to any revision 60 of the setting of the disc 230 only at a time such that an ensuing step of movement will be properly timed thereafter; and, furthermore, at a 65 time when the aligned teeth of the cone gears will be disposed in the path of the axial movement of the pinion 130.

Should the leading end of a raised portion 188, 189, etc. encounter the tongue 132 (which might 70 occur, for example, were the disc 230 permitted to remain in a position presenting a portion thereof between a pair of the notches 280 to the projection 278) the resultant engagement of the tongue 132 by such raised portion would cause said 75 tongue to swing around its pivot 129 against the

tension of the spring 131, thus permitting such raised portion to pass under the free end of said tongue. It will be evident, however, that during the time said tongue is being so swung, or while a raised portion is so passing beneath the free end thereof, movement of said disc 230 to bring one of its notches 280 in registering relation to the raised portion 278, will cause the pinion 130 to be moved into proper engaging relationship with one of the cone gears and thereby carry the 10 tongue 132 to a position where its free end will be moved by the spring 131 into the space between the raised portion which had swung said tongue out of its path and that raised portion which is adjacent thereto and nearest in the side thereof 15 toward which movement of said tongue is urged responsive to the setting of the disc 230.

If it is desired that movements of the tongue 132 shall be permitted only at a predetermined stage of the rotation cycle of the cams 200, 202, 20 there should be such ratio between the shafts 182 and 174 and the spaces between ends of raised portions 188, 189, etc. should be so positioned as to become effective for permitting axial shifting or lengthwise movements of the pinion 130 only during a desired portion of said cam 25 rotation cycle.

The explanations hereinbefore given as to an 30 illustrative application of this invention to certain of the many possible uses thereof, when considered in connection with the accompanying drawing, are believed to be fully sufficient to enable those skilled in this art to apply this invention to all situations to which it is suited; 35 however, as a concrete example of one such application, attention is directed to the fact that the variable timer of this invention might well be utilized as the "master timer" briefly referred to in the co-pending application of Harrison I. Turner and Carl L. Anderson, Serial No. 755,742, 40 filed December 3rd, 1934, for Signal controlling and duration varying system and mechanism therefor.

Claim is made to, and it is desired to secure by 45 Letters Patent of the United States of America, all generic and specific features of the invention shown by the accompanying drawing and as hereinbefore more fully described, including all features which may, as a matter of language, be said to fall between the scope of any of the following: 50

1. In a variable timer; circuit controlling mechanism; change gear mechanism for causing operation of said controlling mechanism at any one of a plurality of diverse speeds, said gear mechanism comprising axially displaced gears of diverse sizes and a pinion movable lengthwise therealong for establishing meshing relationship with various ones of said gears; driving means for said pinion; mechanism operable for preselecting the various aforesaid diverse speeds; shifting mechanism responsive to said selecting mechanism for establishing preselected speeds; and change delay mechanism comprising a delay drum, means for rotating said drum, a guide tongue movable with 60 said pinion axially of said drum, and discontinuous annular raised portions distributed axially along said drum in the path of said tongue and spaced to permit adjacent raised portions to pass freely at respective sides of said tongue when said 65 pinion is positioned for meshing relationships with said gears, the spaces between the ends of each raised portion being sufficient to permit said tongue to pass therethrough.

2. In a variable timer; circuit controlling 75

- mechanism; change gear mechanism for causing operation of said controlling mechanism at any one of a plurality of diverse speeds, said gear mechanism comprising axially displaced gears of diverse sizes and a pinion movable lengthwise therewith for establishing meshing relationship with various ones of said gears; driving means for said pinion; mechanism operable for preselecting the various aforesaid diverse speeds; shifting mechanism responsive to said selecting mechanism for establishing preselected speeds; and change delay mechanism comprising a delay drum, means for rotating said drum, a guide tongue movable with said pinion axially of said drum, and raised portions carried by said drum for restraining axial movement of said tongue incidental to lengthwise movement of said pinion from one to another of said gears, said raised portions being circumferentially displaced one from another.
3. In a variable timer; circuit controlling mechanism; change gear mechanism for causing operation of said controlling mechanism at any one of a plurality of diverse speeds, said gear mechanism comprising axially displaced gears of diverse sizes and a pinion movable lengthwise therewith for establishing meshing relationship with various ones of said gears; driving means for said pinion; mechanism operable for preselecting the various aforesaid diverse speeds; shifting mechanism responsive to said selecting mechanism for establishing preselected speeds; and change delay mechanism comprising a delay drum, means for rotating said drum, a guide tongue movable with said pinion axially of said drum, and raised portions carried by said drum for restraining axial movement of said tongue incidental to lengthwise movement of said pinion from one to another of said gears.
4. In a variable timer; circuit controlling mechanism; change gear mechanism for causing operation of said controlling mechanism at any one of a plurality of diverse speeds, said gear mechanism comprising axially displaced gears of diverse sizes and a pinion movable lengthwise therewith for establishing meshing relationship with various ones of said gears; driving means for said pinion; mechanism operable for preselecting the various aforesaid diverse speeds; shifting mechanism responsive to said selecting mechanism for establishing preselected speeds; and change delay mechanism comprising a delay drum, means for rotating said drum, a guide tongue movable with said pinion axially of said drum, and a raised portion carried by said drum for at times restraining axial movement of said tongue.
5. In a variable timer; circuit controlling mechanism; change gear mechanism for causing operation of said controlling mechanism at any one of a plurality of diverse speeds, said gear mechanism comprising axially displaced gears of diverse sizes and a pinion movable lengthwise therewith for establishing meshing relationship with various ones of said gears; driving means for said pinion; mechanism operable for preselecting the various aforesaid diverse speeds; shifting mechanism responsive to said selecting mechanism for establishing preselected speeds; and change delay mechanism for at times restraining lengthwise movement of said pinion.
6. In a variable timer; circuit controlling mechanism; change gear mechanism for causing operation of said controlling mechanism at any one of a plurality of diverse speeds, said gear mechanism comprising axially displaced gears of diverse sizes and a pinion movable lengthwise therewith for establishing meshing relationship with various ones of said gears; driving means for said pinion; mechanism operable for preselecting the various aforesaid diverse speeds; shifting mechanism responsive to said selecting mechanism for establishing preselected speeds; and change delay mechanism for at times restraining lengthwise movement of said pinion.
7. In a variable timer; driving means; circuit controlling means; change gear mechanism for causing operation of said controlling means at any one of a plurality of diverse speeds, said gear mechanism comprising relatively fixed gears of diverse sizes arranged in an evenly spaced conical group, and a pinion associated with said driving means for rotation thereby, for lengthwise movement substantially parallel with the axis of said gears and for meshing relationship with various ones of said gears; selecting mechanism operable for preselecting the various aforesaid diverse speeds of controlling means operation, said selecting mechanism comprising an adjustable part, two oppositely tensioned springs connected with said part for tensioning responsive to adjustment thereof in one direction and the other, an abutment moving with said part, and arms independently movable for causing the free ends thereof to engage said abutment and associated with said springs for spring urged movement toward said abutment; shifting mechanism for response to preselecting operation of said selecting mechanism, said shifting mechanism comprising a gear and a rack meshing therewith, and a projection moving with said gear and disposed in the path of the spring urged movement of said arms for effecting lengthwise movement of said pinion to establish meshing relationships representative of preselected speeds; and change delay mechanism for at times restraining lengthwise movement of said pinion.
8. In a variable timer; driving means; circuit controlling means; change gear mechanism for causing operation of said controlling means at any one of a plurality of diverse speeds, said gear mechanism comprising relatively fixed gears of diverse sizes arranged in an evenly spaced conical group, and a pinion associated with said driving means for rotation thereby, for lengthwise movement substantially parallel with the axis of said gears and for meshing relationship with various ones of said gears; selecting mechanism operable for preselecting the various aforesaid diverse speeds of controlling means operation; shifting mechanism for response to preselecting operation of said selecting mechanisms, said shifting mechanism comprising a gear and a rack meshing therewith for effecting lengthwise movement of said pinion to establish meshing relationships representative of preselected speeds; and change delay mechanism for at times restraining lengthwise movement of said pinion.
9. In a variable timer; driving means; circuit controlling mechanism; change gear mechanism for causing operation of said controlling mechanism at any one of a plurality of diverse speeds, said gear mechanism comprising relatively fixed gears of diverse sizes arranged in an evenly spaced conical group; and a pinion associated with said driving means for rotation thereby, for lengthwise movement substantially parallel with

the axis of said gears and for meshing relationship with various ones of said gears; selecting mechanism operable for preselecting the various aforesaid diverse speeds; shifting mechanism for response to preselecting operation of said selecting mechanism for effecting lengthwise movement of said pinion to establish meshing relationships representative of preselected speeds; and change delay mechanism for at times restraining lengthwise movement of said pinion.

5 10. In a variable timer; circuit controlling mechanism; mechanism for causing operation of said controlling mechanism at any one of a plurality of diverse speeds; driving means for said mechanism; selecting mechanism operable for preselecting the various aforesaid diverse speeds; shifting mechanism operable responsive to said selecting mechanism for establishing the preselected speeds; and change delay mechanism for 15 controlling the operation of said shifting mechanism.

15 11. In a variable timer; circuit controlling mechanism; change gear mechanism for causing operation of said controlling mechanism at any one of a plurality of diverse speeds, said gear mechanism comprising axially displaced gears of diverse sizes and a pinion movable lengthwise therealong for establishing meshing relationship with various ones of said gears; driving means 20 for said pinion; mechanism operable for preselecting the various aforesaid diverse speeds; shifting mechanism responsive to said selecting mechanism for establishing preselected speeds; and change delay mechanism comprising a delay 25 drum, means for rotating said drum, and a guide tongue movable with said pinion axially of said drum, the surface of said drum including structure presenting a generally spiral effect and situated in the path of and for governing axial movement of said tongue whereby to establish a progressive timing for movement of said tongue.

30 12. In a variable timer; circuit controlling mechanism; change gear mechanism for causing operation of said controlling mechanism at any one of a plurality of diverse speeds, said gear mechanism comprising axially displaced gears of diverse sizes and a pinion movable lengthwise therealong for establishing meshing relationship with various ones of said gears; driving means 35 for said pinion; mechanism operable for preselecting the various aforesaid diverse speeds; shifting mechanism responsive to said selecting mechanism for establishing preselected speeds; and change delay mechanism comprising a delay 40 drum, means for rotating said drum, and a guide tongue movable with said pinion axially of said drum, the surface of said drum including structure presenting a generally spiral effect and situated in the path of and for governing axial movement of said tongue.

45 13. In a variable timer; circuit controlling mechanism; change gear mechanism for causing operation of said controlling mechanism at any one of a plurality of diverse speeds, said gear mechanism comprising axially displaced gears of diverse sizes and a pinion movable lengthwise therealong for establishing meshing relationship with various ones of said gears; driving means 50 for said pinion; mechanism operable for preselecting the various aforesaid diverse speeds; shifting mechanism responsive to said selecting mechanism for establishing preselected speeds; and change delay mechanism comprising a delay 55 drum, means for rotating said drum, and a guide tongue movable with said pinion axially of said

drum, the surface of said drum including structure for governing axial movement of said tongue.

14. In a variable timer; circuit controlling mechanism; change gear mechanism for causing operation of said controlling mechanism at any one of a plurality of diverse speeds, said gear mechanism comprising axially displaced gears of diverse sizes and a pinion movable lengthwise therealong for establishing meshing relationship with various ones of said gears; driving means 10 for said pinion; mechanism operable for preselecting the various aforesaid diverse speeds; shifting mechanism responsive to said selecting mechanism for establishing preselected speeds; and change delay mechanism comprising means for 15 permitting movement of said pinion for changing its meshing relationship with said gears only in periodic steps.

15. In a variable timer; circuit controlling mechanism; change gear mechanism for causing 20 operation of said controlling mechanism at any one of a plurality of diverse speeds, said gear mechanism comprising axially displaced gears of diverse sizes and a pinion movable lengthwise therealong for establishing meshing relationship 25 with various ones of said gears; driving means for said pinion; mechanism operable for preselecting the various aforesaid diverse speeds; shifting mechanism responsive to said selecting mechanism for establishing preselected speeds; and 30 change delay mechanism comprising means for permitting movement of said pinion for changing its meshing relationship with said gears only in periodic steps of predetermined magnitude.

16. In a variable timer; circuit controlling 35 mechanism; change gear mechanism for causing operation of said controlling mechanism at any one of a plurality of diverse speeds, said gear mechanism comprising axially displaced gears of diverse sizes and a pinion movable lengthwise 40 therealong for establishing meshing relationship with various ones of said gears; driving means for said pinion; mechanism operable for preselecting the various aforesaid diverse speeds; shifting mechanism responsive to said selecting mechanism for establishing preselected speeds; and change delay mechanism comprising means for 45 permitting movement of said pinion for changing its meshing relationship with said gears only in predetermined relationship to circuit controlling 50 mechanism operation.

17. In a variable timer, driving means, circuit controlling mechanism operable by said driving means, speed change mechanism for effecting variations of the speed imparted to said controlling mechanism by said driving means, mechanism operable for preselecting various diverse speeds, shifting mechanism responsive to said selecting mechanism for causing said speed change mechanism to establish preselected speeds, 60 and change delay mechanism associated with said preselecting mechanism and said speed change mechanism, said delay mechanism comprising means for establishment of said speed variations only in periodic steps of predetermined magnitude and in predetermined relationship to circuit controlling mechanism operation.

18. In a variable timer, driving means, circuit controlling mechanism operable by said driving means, speed change mechanism for effecting 70 variations of the speed imparted to said controlling mechanism by said driving means, mechanism operable for preselecting various diverse speeds, shifting mechanism responsive to said selecting mechanism for causing said speed 75

- change mechanism to establish preselected speeds, and change delay mechanism associated with said preselecting mechanism and said speed change mechanism, said delay mechanism comprising means for establishment of said speed variations only in steps of predetermined magnitude.
19. In a variable timer, driving means, circuit controlling mechanism operable by said driving means, speed change mechanism for effecting variations of the speed imparted to said controlling mechanism by said driving means, mechanism operable for preselecting various diverse speeds, shifting mechanism responsive to said selecting mechanism for causing said speed change mechanism to establish preselected speeds, and change delay mechanism associated with said preselecting mechanism and said speed change mechanism, said delay mechanism comprising means for establishment of said speed variations only in predetermined relationship to circuit controlling mechanism operation.
20. In a variable timer, driving means, circuit controlling mechanism operable by said driving means, speed change mechanism for effecting variations of the speed imparted to said controlling mechanism by said driving means, mechanism operable for preselecting various diverse
- speeds, shifting mechanism responsive to said selecting mechanism for causing said speed change mechanism to establish preselected speeds, and change delay governing mechanism associated with said preselecting mechanism and said speed change mechanism.
21. In a variable timer, driving means, driven means operable by said driving means and having a time cycle, speed change mechanism for effecting variations of the speed imparted to said driven means by said driving means, mechanism operable during the operative cycle of said timer for preselecting diverse speeds, shifting mechanism rendered active responsive to said preselecting mechanism for causing said speed change mechanism to establish preselected speeds, and change delay governing mechanism associated with said preselecting mechanism and said speed change mechanism.
22. In a variable speed timer, means for effecting operation of said timer at any one of a plurality of diverse speeds and changing means presetable during the operative cycle of said timer for effecting predetermined alterations of said timer speed at predetermined intervals, said alterations occurring without further manipulation by an operator.

ERNEST RICHARD FREEBERG.
